ATTACHMENT FOR MACHINES FOR MAKING
CLAY SHINGLESJohn B. Nelson, Manly, and Arthur J. Moore,
Mason City, Iowa

Application November 1, 1930. Serial No. 492,816

5 Claims. (Cl. 25—1)

This invention relates to an attachment for a clay shingle making machine, the general object of the invention being to provide means for automatically punching holes in the shingles 5 without waste of material as the clay member passes from the die to the cutting means.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings 15 wherein like characters denote like or corresponding parts throughout the several views, and in which:—

Figure 1 is a plan view showing portion of a shingle making machine, with our invention applied thereto.

Figure 2 is an elevation of Figure 1.

Figure 3 is a section on line 3—3 of Figure 2.

Figure 4 is a section on line 4—4 of Figure 2.

Figure 5 is a bottom plan view of portion of a 25 carrier or pallet.

As is well known, the forming mechanism of a clay shingle making machine forms the clay into a rectangular member having two vertical partitions therein, with the four sides and the 30 two partitions, when separated, forming six shingles. This member passes from the forming device or die upon the carriers or pallets 1 which carry the member to cutting means which cuts the member into blocks, these blocks being divided into the shingles, as before described. The 35 pallets are connected to the endless chains 2 supported by the rolls 3 at the ends of the table A, only one of these rolls being shown.

In carrying out our invention, we provide a 40 frame B above the table A, this frame consisting of two bars 4 fastened to the upright member 5 at the die end of the table and having their other ends connected together by a cross piece 6. A member or block 7 is slidably arranged on this 45 frame by having holes therein through which the bars pass and the lower part of the block is formed with an opening 8 through which the clay member passes. This member is shown at X in dotted lines in Figures 1 and 2. A shaft 9 is rotatably supported at the upper part of the member or block 7 and has its ends cranked, as 50 at 10, one crank being longer than the other and this long crank is adapted to engage the bent end of a post or upright 11 on the table when 55 the block has been moved to a certain extent toward the cross piece 6. The cranks 10 are adapted to be engaged by the bent ends of the uprights or posts 12 on the pallets, these uprights being on the pallets of machines as now 60 constructed.

A cable 13 is attached to a rod 14 carried by the block 7 and passes over the guiding pulleys 15 on the member 5 and has a weight 16 attached to its other end, this weight acting to hold the block against the stop 17 on the frame 65

B. Thus it will be seen that as the pallets move along, the posts or uprights 12 on each pallet will strike the cranked ends 10 of the shaft 9 and thus cause the block 7 to move with the pallet until the long crank 10 strikes the stationary 70 upright 11, which causes the shaft to turn until the cranked ends 10 pass above the posts or uprights 12, when the weight 16 will return the block 7 against the stop 17, where it will be in position to be engaged by the uprights of the 75 next pallet, which move it forwardly, as before described. A pair of punch pins 18 is slidably arranged in each side of the block and in the top, these pins projecting into the opening 8 when the pins are in operative position so that 80

they will punch holes in the member X from the sides and top thereof and the side pins are made long enough so that they will extend through the side parts as well as the partitions of the clay member. Each set of pins is fastened to a 85 plate 19, the top plate being connected by a link 20 with a lever 21 pivoted to the top of the block and the side plates being connected by the links 22 with the shafts 23 passing through the block and each shaft has an arm 24 thereon 90 which is connected by a link 25 to the lever 21. This lever has a weight 26 thereon which tends to hold the lever in lowered position with the pins in retracted position, but when the lever is raised, the connections between the levers and 95 the plates 19 which carry the pins will project the pins into the opening 8 and thus cause the pins to perforate the clay member. As shown, the block is formed with an extension 7' in which the pins are located, the extension being of less 100 area than the block so that the levers and links can be pivoted to the main part of the block to operate the pins carried by the extension.

An arm 27 is carried by the frame B and an L-shaped lever 28 is pivoted to the arm, with one portion of the lever 28 adapted to rest on the arm under the action of gravity. In this position, the lever is in an inclined position so that as the block moves forwardly or with a pallet, a bent part 29 of the lever 21 will engage the lever 28 and ride up the same so that the weighted lever 21 is raised and thus causes the pins to be projected into the clay member. As the part 29 rides off the upper end of the lever 27, the weighted lever will drop so that the pins will be retracted and as the weight 16 pulls back the block, the bent part 29 will pass under the lever 28, swinging the same on its pivot until the parts pass each other so that said part 29 will be 115 120

in position to again ride up the lever 28 on the forward movement of the block.

A double lever 30 is pivoted to the forward end of each pallet on the under side thereof, and 5 has a pair of punch pins 31 at its other end which pass through holes in the pallet. A weight 32 on the lever 30 tends to hold the same in lowered position, with the pins flush or substantially so with the top of the pallet. The table top is 11 formed with an inclined part 33 which will engage the double lever arrangement as the pallet moves forwardly so as to swing the double lever upwardly against the action of its weight and thus project the pins 31 into the bottom of the clay 15 member. As the pallet nears the other end of the table, it rides down a similar portion 33' so that the weighted levers can drop and thus 20 retract the pins. The parts are so positioned and arranged that the holes made by the punches or pins 18 in the block will register with those made in the bottom of the member by the pins 31.

Thus it will be seen that we have provided 25 automatic means whereby a pair of holes will be punched in each shingle forming part of a clay member which is adapted to form six shingles when the parts are separated. These holes, of course, act to receive the nails which are used to fasten the shingles in place. It will, of course, be understood that the parts, wherever necessary or desirable, can be made adjustable and that 30 springs or other means can be used instead of the weights and if desired, the block can be returned to its normal position by means operated by the pallets on the lower reach of the endless member.

The block may be provided with rollers or other anti-friction means which engage the parts of the frame B and a shock absorbing spring 40 17' may be provided for absorbing the shocks due to the block striking the stop means, this spring also tending to start the block on its return movement. Of course, a stop 17 and its spring may be placed on the other member of the frame B, if desired.

45 It is thought from the foregoing description that the advantages and novel features of the invention will be readily apparent.

It is to be understood that changes may be 50 made in the construction and in the combination and arrangement of the several parts, provided that such changes fall within the scope of the appended claims.

What we claim is:—

1. In combination with a clay shingle forming 55 machine and in combination with its pallet table and the pallets, a frame supported above the table, a carriage slidably arranged on the frame, side and top punches carried by the carriage, means for normally holding the carriage in retracted position, means for causing the carriage to move forwardly with a pallet a certain distance, after which the carriage is released from the pallet, means on the frame and carriage operated by longitudinal movement of the latter for 60 projecting the punches as the carriage moves forwardly and retracting the punches just before it reaches its forward limit of movement and separate lever means on the pallet and cooperating means on the table for punching holes in the 65 bottom of the clay member.

2. In combination with a clay shingle forming 70 machine including its pallet table and pallet, a

frame supported above the top of the table, a carriage slidably arranged on the frame and having an opening therein through which the clay member passes, means for normally holding the carriage in retracted position, a crank shaft on the carriage having cranks engaged by means on the pallets as the pallets move forwardly whereby the carriage will move forwardly with the pallets, a stop on the table engaging a part of the shaft for releasing the cranks thereof from the uprights after the carriage has moved a certain distance with a pallet, side and top punches carried by the carriage, a weighted lever connected with the punches and normally holding the same in retracted position, trip means carried by the frame and extending longitudinally thereof and engageable with the weighted lever for raising the weighted end of the lever as the carriage moves forwardly for projecting the punches through the sides and top of the clay member, separate means carried by each pallet for punching holes in the bottom of the clay member as the pallet moves forwardly over the table, and means on the table cooperating with said last named means for actuating the same. 95

3. In a shingle forming machine including a table, pallets movable longitudinally thereon for supporting a clay member, and means for advancing the pallets, a frame supported above the table, a carriage slidably longitudinally of the 105 frame and normally held at one limit of its movement, means for advancing the carriage as each pallet moves forwardly, horizontally and vertically arranged punches slidably mounted in the carriage, lever arms carrying the respective 110 punches, a link and lever mechanism connected with said lever arms, and means operable upon longitudinal movement of the pallets for moving said link and lever mechanism for causing the punches to perforate the shingles. 115

4. In a shingle forming machine including a table, pallets movable longitudinally thereon for supporting a clay member, and means for advancing the pallets, a frame supported above the table, a carriage slidably longitudinally of the 120 frame and normally urged toward one limit of its movement, means for advancing the carriage as each pallet moves forwardly, horizontally and vertically arranged punches slidably mounted in the carriage, lever arms carrying the respective 125 punches, means connected with said lever arms including an actuating lever normally urged in one direction, and means carried by the frame and engageable by said actuating lever upon movement of the pallets. 130

5. In a shingle forming machine including a table, pallets movable longitudinally therealong for supporting a clay member, and means for advancing the pallets, a frame supported above the table, a carriage slidably longitudinally along 135 the frame and normally urged toward one limit of its movement, means for advancing the carriage as each pallet moves forwardly, a plurality of punches slidably mounted in the carriage, lever arms carrying the respective punches, a link, lever 140 and rock shaft mechanism connected with said lever arms and including a main actuating lever, and trip means carried by the frame and engageable with said actuating lever upon movement of the pallets. 145
